REMOVABLE SPIKE PLATE FOR SPORT SHOES

Warren B. Hastings, Jr., Norfolk, Va.

Application June 6, 1945, Serial No. 597,885

3 Claims. (Cl. 36—7.7)

This invention relates to removable spike plates for sport shoes.

An object of the present invention is to provide a removable spike plate which will be light, simple in construction, easily applied and removed and which will effectively grip the sole of the shoe to which it is applied.

A further object of the invention is to provide a device of the character indicated of improved and simplified construction requiring no tools, keys or the like, for operation and involving a unitary structure.

The invention consists in the novel construction arrangement and combinations of parts hereinafter more particularly described and claimed.

One sheet of drawings accompanies this specification as part thereof in which like reference characters indicate like parts throughout.

In the drawing:

Fig. 1 is a bottom plan view of the improved device applied to the sole of the shoe.

Fig. 2 is a transverse cross section taken on line 2—2 of Fig. 1.

Fig. 3 is a transverse cross section taken on line 3—3 of Fig. 1.

Fig. 4 is a perspective view of the improved device.

In accordance with the present invention a plate of preferably spring metal such as brass or steel is provided conforming generally to the shape of the sole of a shoe.

As herein illustrated the main portion of the plate 1 is provided upon its outer face with a plurality of spaced and preferably staggered spikes 2.

The rear portion of the plate 1 is formed with two marginal extensions 4—4, the rear ends of each of said extensions 4—4 being provided with oppositely disposed extensions 8 and 10 adapted to be arranged in superposed relationship, each of these extensions 8 and 10 being passed through guide slots 7—7 formed through portions of the plate struck up from the plane of the plate and indicated as 5 and 6. The end of each of these extensions 8 and 10 are provided with sole engaging clips 9 and 11.

Adjacent the toe end of the plate 1 are provided marginally disposed sole clips 3—3 extending marginally from the sole plate 1.

In applying the improved spike plate to the shoe the toe clips 3—3 will be engaged over the edge of the shoe sole adjacent the toe end, then the rearwardly extending marginal extensions 5 4—4 will be compressed toward each other in the plane of the plate, thus forcing the rear wall clips 9 and 11 apart to permit the engagement of same over the edge of the sole. Upon the release of the marginal extensions 4—4 the rear sole clips 10 9 and 11 will be drawn inwardly, thus efficiently locking the sole plate into engagement with the shoe sole.

Various minor modifications will readily suggest themselves to those skilled in the art but within 15 the scope of the present invention as claimed.

Having thus fully described my invention, I claim:

1. Slip-on spike plate for shoes, comprising a plate of resilient metal shaped and sized to conform with the sole of a shoe, said plate provided with a plurality of spaced spike members extending from one face thereof and having oppositely disposed sole engaging clips marginally positioned adjacent the toe end, the rear end of said plate 20 formed as two marginal extensions, each of said extensions formed at the rear end with inwardly directed extensions adapted to overlap and formed at their outer ends with sole engaging clips.

2. The device of claim 1 with means adjacent 30 the rear end of each of said rear extensions of the plate to guide the inwardly directed extension associated with the other of said extensions.

3. Slip-on spike plate for shoes, comprising a plate of resilient metal shaped and sized to conform with the sole of a shoe, said plate provided with a plurality of spaced spike members extending from one face and having two rearwardly extending marginal arms, sole clips formed on the toe end of the plate and sole clips at the rear 35 end of the plate one on each side, each of said rear sole clips rigidly associated with the opposite rearwardly extending arm whereby the flexing of said arms in the plane of the plate separates said rear clips to permit engagement with 40 the side of a shoe.
